DRYING KILN

Hermann Geul, Stuttgart-Hedelfingen, Germany

Application March 23, 1953, Serial No. 344,110

Claims priority, application Germany October 3, 1952

3 Claims. (Cl. 34—223)

This invention relates to a kiln. In particular, the invention is directed to the drying of piles of material separated into horizontal layers by spacers.

Ordinarily in kilns, stacks of lumber or other material are dried by air or steam forced by blowers around and between the layers of material. The drying system conventionally included a rather elaborate housing for the system of conduits and blowers and wasted a good part of the drying energy, in spite of the expensive plant construction.

The object of the instant invention is to construct a kiln of simple, efficient structure, which makes maximum use of the drying medium.

In general, this and other objects of the invention are accomplished by stacking the material to be dried in horizontal layers separated by spacers, and constructing a kiln which closely fits the stacked material with just sufficient wall space being provided to house a fan, heating elements, and curved baffle walls. The fan is of a size such that air is pulled by suction through one-half of the piled material, deflected by curved walls and blown under pressure through the other half of the piled material, and then again deflected by curved walls into the suction area. One or more fans can be used to circulate the drying medium.

The means by which the objects of the invention are obtained are described more fully with reference to the accompanying drawings, in which:

Figure 1 is a cross-sectional view through a kiln constructed according to the invention;

Figure 2 is a cross-sectional view of a first modified form of kiln;

Figure 3 is a cross-sectional view of a second modified form of kiln;

Figure 4 is a cross-sectional view of a third modified form of kiln;

Figure 5 is a horizontal cross-sectional view of a fourth form of kiln; and

Figure 6 is a vertical cross-sectional view of the kiln shown in Figure 5.

As shown in Figure 1, the kiln 1 encloses a chamber in the bottom of which are tracks upon which a carriage 3 can be run. The kiln is designed so that the ceiling 4 barely clears material carried by the carriage, and the lower side walls are as close as possible to the carriage from the ground to points 5 which are equal to the height of the carriage. This carriage supports a pile of lumber, or other material 6, the horizontal layers being separated by spacers 7 so that air may circulate between the layers.

A fan 8 is mounted on one side wall halfway of the height of the pile of material. This fan has a diameter equal to one-half the major dimension of the pile of lumber. In this figure the height of the pile is greater than its horizontal length, so that the fan covers one-half the height of the pile. Heating pipes 9 are mounted above and below the fan.

The inner side walls of the chamber are curved to provide for the circulation of the air by fan 8. The walls

2

are curved so that an apex 12 is formed on the line of the axis of the fan, and thus there appears an upper curved section 13 and a lower curved section 14 on the side wall opposite fan 8, and similarly curved walls adjacent the fan. As the kiln closely encompasses the pile of material, the drying gases may circulate only through the layers of material in a most efficient manner. The system is such that the pile may be considered to be divided vertically into four quarters. Curved wall 13 recircles drying gas passing through the upper two quarters, while curved wall 14 likewise serves the lower two quarters. Half of the pile is subject to suction flow of the drying gas, while the other half of the pile is in a pressure zone.

As shown by the arrows, the fan 8 acts as a suction fan to draw air through the center two quarters of the pile of lumber, and this air is directed by the curved wall to be circulated under pressure through the heating pipes 9 and through the top and bottom quarters of the pile of lumber. The air, after passing through the pile, strikes curved walls 13 and 14, respectively, to be thus directed toward the middle two quarters of the pile, where it is drawn by suction through the pile. Due to the closeness of the fitting of the walls, all the heating air is confined to the pile and is efficiently employed to dry the lumber. The air is constantly recirculated, and conventional valves may be employed to permit the escape of air saturated with moisture drawn from the lumber.

In Figure 2 the structure is modified by employing a blower fan 8' on the opposite side of the chamber from fan 8. The circulation of the drying medium is as described for Figure 1, additional rapidity of circulation being obtained by the second blower.

In Figure 3 the structure is modified by placing the suction fan 8 opposite the upper half of the pile of lumber with the heating pipes 9 covering the lower vertical half of the pile. The side walls of the chamber are thus curved so that air is drawn by suction through the upper half of the pile and circulated under pressure through the lower half of the pile.

In Figure 4 the structure of Figure 3 is further modified by putting a second suction fan on the opposite side of the pile adjacent the lower half of the pile, and a second set of heating pipes 9 above this second fan. A more rapid circulation is obtained by the dual arrangement.

The direction of travel of the drying gas in Figures 1 to 4, is horizontally through the pile, and then vertically along the curved walls to a different horizontal passage.

In Figures 5 and 6 the air is again passed horizontally through the pile, but it is reversed in direction in the same horizontal plane. Vertically extending curved walls 12 and 13 are joined at apex 12 which is perpendicular to the line of the axis of suction fan 8. The kiln is of greater length than height, so that while the diameter of the blower is the same as the height of the pile, the fan extends only across the middle two quarters of the length of the pile. Air is drawn by suction through the middle quarters and then directed by the curved walls in horizontal flow, across heating pipes 9, and then through the end quarters, respectively, of the pile. Curved walls 13 and 14 then direct the air to the middle quarters, the horizontal flow being maintained. On the pressure side of this system, a conduit 10 having a throttle 11 communicates with the fan so as to form a steam outlet.

Although the structure of Figures 1 to 6 shows a stationary pile of goods on carriage 3, such can be replaced by a conveyor belt for the continuous passage of material through the chamber. Again, a plurality of superimposed conveyor belts can be placed in the chamber, this being especially suitable for drying sheets of veneer.

The advantages of the invention are in the simplicity of the construction of the chamber, and the efficiency of

operation due to the fact that the chamber very closely encompasses the pile of lumber. No elaborate conduit systems are involved, and all of the drying action of the gaseous medium is directed to the material being dried rather than an extraneous structure.

Having now described the means by which the objects of the invention are obtained,

I claim:

1. A kiln for drying materials arranged in a pile of horizontal layers vertically spaced apart comprising a chamber having all its inner walls closely encompassing the pile, a suction fan having a diameter equal to one-half of the major dimension of the pile mounted on one side wall of said chamber with its blades vertically extending over the middle two-quarters of the height of the pile and rotatable in a plane in close clearance with the pile; a first curved surface in said wall extending from the axis of said fan to an end of said chamber for directing drying gas moved by said fan to the part of the chamber not covered by said fan whereby the drying gas will flow under pressure through said pile to the opposite side wall, a second curved surface oppositely facing said first surface for directing the drying gas without substantial loss of velocity to the portion of said pile lying opposite said fan and then through said pile to said fan for recircula-

tion, and similar curved surfaces extending from the axis of said fan to the other end of said chamber.

2. A kiln as in claim 1, further comprising a blower fan mounted on said opposite side wall, said blower fan having a size similar to said suction fan.

3. A kiln as in claim 2, further comprising said blower fan being mounted in axial alignment with said suction fan.
